Letters Patent, No. 886, Dated May 19, 1857.

The schedule referred to in these Letters Patent, and making part of the same,

To all to whom these Presents shall come:

Be it known that we, Jacob Beesley & Edward J. De-
lany of Philadelphia, and State of Pennsylvania, have invented a new design
for Cooking Stoves, and that the following is a full, clear and exact description
of the principle or character which distinguishes it from all other things before
known and of the usual manner of making, modifying and using the same,
reference being had to the accompanying drawings.

Figs: 1 & 4, Represents the side complete with over door illustrating the design thereof.

Fig: 2, Represents the bottom plate illustrating the design thereof.

Fig: 3. Represents the front and front doors of
store illustrating the design thereof.

These drawings illustrate our design for the Cooking Stove, other parts of the stove being plain and ornamental at pleasure.

What we claim as our invention is the design for looking stoves as hereinabove illustrated and set forth.
